UNITED STATES PATENT OFFICE.

FREDERICK M. FURBER, OF REVERE, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

CARBURETER.

1,396,184.

Specification of Letters Patent.

Patented Nov. 8, 1921.

Application filed July 3, 1916. Serial No. 107,344.

To all whom it may concern:

Be it known that I, FREDERICK M. FURBER, a citizen of the United States, and resident of Revere, in the county of Suffolk and State 5 of Massachusetts, have invented certain Improvements in Carbureters, of which the following description, in connection with the accompanying drawings, is a specification, like reference-characters on the drawings 10 indicating like parts in the several figures.

This invention relates to machines for impregnating a current of gas with a volatile hydrocarbon in order to form a combustible or explosive mixture, and in particular to 15 carbureters which impregnate air with gasolene to make combustible gas for heating or lighting purposes.

It is necessary in many arts, for example 20 in shoe manufacture, to heat various tools. Electricity, steam and ordinary illuminating gas are often used for this purpose. When these are unavailable, or too costly, gasolene-impregnated air is often used. Such gas is also frequently used as an illuminant.

25 It is found that the gasolene now commercially obtainable consists in part of heavier components, the vapor pressure of which at ordinary factory temperatures is not high enough to cause sufficient evaporation into 30 air at 16 or 18 pounds (absolute) pressure to make a combustible mixture. The lighter components of the gasolene evaporate rapidly and make a satisfactory gas, but unless the apparatus is continually refilled with 35 fresh gasolene it is found that the gas becomes poorer and poorer until it finally becomes incombustible, with the heavier parts of the gasolene still remaining in the carbureter.

40 In order to evaporate the gasolene completely and in sufficient quantities it is necessary to apply heat to the evaporating chamber. It is regarded as unsafe to use a flame for this purpose and electric heat is unavailable in many places. It is an object of my 45 invention to obviate the difficulty described and to provide an apparatus which shall be safe and convenient in use.

To this end a feature of my invention consists in a carbureter having a hydrocarbon chamber and a gas compressor in thermal 50 communication with said chamber so that

heat generated by the compression of the gas may be communicated to the hydrocarbon in the chamber.

55

Another feature of my invention is a carbureter having a hydrocarbon chamber, a water jacket in said chamber and a gas compressor enveloped by said water jacket whereby the temperature and pressure of the 60 hydrocarbon in the chamber are maintained below safe limits.

Other features of the invention, comprising other arrangements and combinations of parts, will be described in the specification 65 and pointed out in the claims.

Figure 1 of the drawing shows in section a preferred embodiment of the invention.

Fig. 2 illustrates a modification.

The gas chamber 1, having the outlet valve 70 2 for removal of the gas formed in the apparatus, contains a cup 3. The upper portion of the cup 3 is broadened out into a pan 4. The nipple 5 communicates with the chamber 1, extends below the top of the pan 4, 75 and contains the spring pressed valve plunger 6 which seats upward at the top of the nipple. It has a rod 6' which strikes the bottom of the valve chamber when the valve opens and arrests the downward movement 80 of the plunger. The supply can or filler 7 has a similar valve 8, and the can 7 and nipple 5 are furnished with complementary portions of a bayonet joint 9 so that the can may be fitted securely down on the upper 85 end of the nipple and fastened. The rod 10 which forms a part of the valve plunger 8 extends through the channel formed by the nipple and can and when the can is fitted over the nipple and forced down the rod 10 90 unseats the lower valve plunger, the spring of which is weaker than that of the upper valve. The lower valve plunger descends until its rod 6' contacts the bottom of its chamber, and the completion of the engagement of the can with the nipple unseats the upper valve.

Gasolene will flow from the can 7 down into the pan 4 and cup 3 until its level reaches the bottom of the nipple 5, when a 100 constant level will be maintained on the barometric feed principle. The gasolene in the carbureter can therefore never exceed a definite quantity. It will be clear also that

there will be no danger of ignition or accident in filling because both valves at 6 and 8 remain closed at all times except when the supply can and the nipple are well engaged.

5 A shaft 11 journaled in the casing of the machine and driven by the pulley 12, reciprocates the piston 13 in the cylinder 14. The piston has a spring pressed ball valve 15 in its lower end. Between the extreme positions of the piston a channel 16 leads out of the cylinder, having two valved outlets 17, 18. The valve at 17 is set at the pressure it is desired to maintain in the gas chamber 1. The valve at 18 is set to open at very low pressure. When the piston descends toward the channel 16, the compressed air below it will flow through the channels 16, 18 until the pressure in the chamber 1 reaches the point where the valve at 17 opens and lets the compressed air out into the room. When the valve 2 is open a continuous current of air is thus kept flowing through the gas chamber, over the gasoline in the pan 4.

The lower end of the cylinder 14 is extended and constricted at 19, and the cylinder is surrounded by a water jacket 20, having an outlet valve 21. This water jacket and cylinder extension 19 extend downward into the cup 3. During the lower part of 30 the stroke of the piston 13, after it passes the channel 16, it compresses the air in the extension 19, and the temperature of this air rises. Heat consequently begins to flow through the walls of the cylinder into the water jacket, through which it is communicated to the gasoline in the cup 3. As the pressure rises in the extension 19 some of the heated air will leak past the piston, and as the piston rises air enters through the valve 40 15 to replace this air and that which has been forced out the channel 16. The air in the extension 19 is, therefore, being continually renewed, to a certain extent. The purpose of the water jacket 20 is to prevent the 45 temperature of the gasoline and consequently its vapor pressure from rising above a safe limit. The gasoline can get no hotter than boiling water, and its vapor pressure at this temperature is not dangerous.

50 If desired, an escape valve 22 may be placed at the bottom of the extension 19 to permit a large quantity of the compressed heated air to escape, so that the heating portion of the machine will work exactly as the 55 familiar bicycle pump. That is, the expansion and consequent cooling of the heated air will take place outside the compression chamber, so that no substantial quantity of heat once imparted to the walls of the chamber will be returned by them to the air in the chamber. It has been found, however, that the apparatus operates satisfactorily without the incorporation of this feature.

It is clear, also, that the apparatus works 60 like the bicycle pump during the upper part

of the down stroke before the piston reaches the channel 16.

What seems to happen is that the compression which takes place is somewhere between isothermal and adiabatic, and probably approximates the latter more closely than the former, only a slight amount of heat passing from the air to the cylinder walls during the very rapid compression. (The pump is run at several hundred R. P. M.) The compressed air escapes through the valves at 17 and 22, and by leakage, to a certain extent, so that its expansion and consequent cooling take place at a distance from the cylinder, and the heat communicated to the cylinder is not all reclaimed. The very rapid recurrence of the cycle and consequent rapid multiplication of the heat quantity imparted in one cycle enables the cylinder walls to transmit a considerable quantity of heat to 85 the hydrocarbon.

Having described my invention, what I claim as new and desire to secure by Letters Patent of the United States is:

1. In a machine of the class described, an evaporating chamber and a gas compressor located in said chamber whereby some of the heat of compression may be utilized to produce a substantial rise in temperature in the liquid in the evaporating chamber.

2. In a machine of the class described, an evaporating chamber, a gas compressor and a water jacket surrounding said compressor, the jacket being arranged in direct thermal communication with the liquid in the chamber.

3. In a machine of the class described, an evaporating chamber, and a gas compressor constructed and arranged to develop pressures substantially greater than atmospheric, and having through its walls thermal communication with the evaporating chamber, whereby some of the heat developed in the compression may be utilized to heat the liquid in the evaporating chamber.

4. In a machine of the class described, a hydrocarbon chamber, means for maintaining a shallow body of hydrocarbon in said chamber, a cylinder having an opening into said chamber, said cylinder extending into said chamber, and a piston in said cylinder.

5. In a machine of the class described, a hydrocarbon chamber, a cylinder having an opening into said chamber, to cause a flow of air over hydrocarbon in said chamber, said cylinder extending into said chamber, and a piston in said cylinder traveling across said opening.

6. In a machine of the class described, a hydrocarbon chamber, a water jacket in said chamber, and a gas compressor enveloped by said water jacket.

7. In a machine of the class described, a hydrocarbon chamber, a pan in said chamber having a depressed cup, a gas compressor

- in said cup, and means for causing gas from the compressor to flow over hydrocarbon in said pan.
8. In a machine of the class described, a low pressure hydrocarbon chamber, a cylinder extending into said chamber, a piston in the cylinder to compress air therein, an outlet pipe from the cylinder leading into the hydrocarbon chamber, the cylinder, piston and pipe being constructed and arranged to stand pressures of several atmospheres, and a relief valve in said pipe permitting escape of air when the pressure in the chamber has reached a predetermined point.
9. In a machine of the class described, a low pressure hydrocarbon chamber, a cylinder extending into said chamber, a piston in the cylinder to compress air therein, an outlet pipe from the cylinder leading into the hydrocarbon chamber, and a relief valve in said pipe permitting escape of air when the pressure in the chamber has reached a predetermined point.
10. In a machine of the class described, a low pressure hydrocarbon chamber, a cylinder extending into said chamber, a piston in the cylinder to compress air therein, an outlet pipe from the cylinder leading into the hydrocarbon chamber, the cylinder, piston and pipe being constructed and arranged to stand pressures of several atmospheres, and a relief valve in said pipe permitting escape of air when the pressure in the chamber has reached a predetermined point.

In testimony whereof I have signed my name to this specification.

FREDERICK M. FURBER.
